UNITED STATES PATENT OFFICE

92,639

DESIGN FOR A REFRIGERATOR

Everett Worthington, Chicago, Ill., assignor to
Coca-Cola Company, Atlanta, Ga., a corpora-
tion of Delaware

Application March 24, 1934, Serial No. 51,172

Term of patent 14 years

To all whom it may concern:

Be it known that I, EVERETT WORTHINGTON, a citizen of the United States residing at Chicago, in the county of Cook and State of Illinois, have invented a new, original, and ornamental Design for a Refrigerator, of which the following is a specification, reference being had to the accompanying drawing, forming part thereof.

Figure 1 is a perspective view of a refrigerator showing my new design.

Figure 2 is a side elevation.
Figure 3 is a top plan view.
Figure 4 is a side elevation, and
Figure 5 is a side elevation thereof.

I claim:

The ornamental design for a refrigerator as shown.

EVERETT WORTHINGTON.
